UNITED STATES PATENT OFFICE.

WILLIAM HARVEY, OF PHILADELPHIA, PENNSYLVANIA, AND EDWARD OSBORN, OF NEW YORK, N. Y., ASSIGNORS TO THEMSELVES, AND JOHN WATTS AND JOSEPH WATTS, OF PHILADELPHIA, PENNSYLVANIA.

DESIGN FOR HANDLE FOR CANES.

SPECIFICATION forming part of Design No. 22,083, dated December 27, 1892.

Application filed October 17, 1892. Serial No. 449,160. Term of patent 3½ years.

To all whom it may concern:

Be it known that we, WILLIAM HARVEY, residing at Philadelphia, in the State of Pennsylvania, and EDWARD OSBORN, residing at New York, in the State of New York, citizens of the United States, have invented and produced a certain new and original Design for the Handle of a Cane or Umbrella-Stick, of which the following is a specification, reference being had to the accompanying drawings, forming part hereof, and in which—

Figures 1 and 2 are respectively perspective views of the obverse and reverse of a cane or umbrella stick handle comprising the features of our invention.

The leading features of our design for the handle of a cane or umbrella comprise a handle representing a globe or chart having a collar provided with an annular rib and with a portrait or raised head having a ruching displayed about the neck thereof.

Referring to the drawings, *a* is the handle of the cane or umbrella stick having repre-

sented thereon a globe or chart comprising the two hemispheres with the water and earth surfaces thereof. *b*, is a portrait or raised head with a ruching *b'*, displayed about the neck thereof. The handle *a*, is provided with a collar *b*, having an annular bead-like rib *e*, formed therewith in order to give an ornamental appearance or finish to the handle of the cane or umbrella stick.

Having thus particularly described the characteristic features of our design, what we claim as new and desire to secure by Letters Patent is:—

The design for the handle of a cane substantially as shown and described.

In witness whereof we have hereunto set our signatures in the presence of two subscribing witnesses.

WILLIAM HARVEY.
EDWARD OSBORN.
